UNITED STATES PATENT OFFICE

ARTHUR T. BRENNAN, OF DETROIT, MICHIGAN

WINDOW STRUCTURE

Application filed May 31, 1930. Serial No. 458,868.

My invention relates to window structures and has particular reference to that type wherein sliding sashes are used as distinguished from the type known as casement 5 windows.

An object of my invention is to eliminate the necessity of sash-weights for the purpose of retaining the upper and lower sashes in any position to which they may be adjusted. 10 By so doing I eliminate a large portion of the expense involved in the manufacture and assembly of such window structures.

Another object of my invention is to so design the frame members of the sash units 15 and the means for retaining them in position after adjustment that the complete assembly constitutes a fully weather stripped unit in itself and eliminates the necessity of providing independent units for the purpose 20 of weather stripping the structure.

Still a further object of my invention is to provide a yieldable assembly wherein the sash members may be racked to some extent without distortion or breakage of any of the 25 elements. This is an extremely advantageous feature inasmuch as all window structures are subjected to a greater or lesser extent, to pulls and twists of various sorts due to the incessant raising and lowering of the 30 sashes and other manipulations thereof for divers and sundry purposes.

In accomplishing the above objects I have provided guide strips of flexible sheet metal which cooperate with grooves extending 35 along the sides of the sash members, and still another meritorious feature involved in my invention is the particular shape of these guide strips. I have so designed them that there are several points of direct contact with 40 the sash grooves, each of which points may be easily and firmly adjusted to exert a greater pressure inwardly on the sashes. In this way it is a very simple matter to adjust the structure to hold each of the sashes firmly in an 45 adjusted position in case there should develop a tendency for them to slide downward along the guide strips after a long period of usage, a difficulty which not infrequently occurs with any sash type of window.

50 Yet a further object of my invention is to

provide sash frame members rolled from sheet metal into a shape which is designed to cooperate in a most efficient manner with the weather stripping, glass panes, and certain other novel features to be described hereafter, as well as constitute a light, easily manipulated assembly. 55

Various other objects and meritorious features of my invention will appear from the following description taken in conjunction 60 with the drawings wherein like numerals refer to like parts throughout the several figures and wherein:

Fig. 1 is a front elevation of my window structure assembly, 65

Fig. 2 is a section through the top frame member of the upper sash,

Fig. 3 is a section through the lower frame member of the upper sash and the upper frame member of the lower sash when the window 70 is closed,

Fig. 4 is a section through the lower frame member of the lower sash, and

Fig. 5 is a section on line 5—5 of Fig. 3.

In Fig. 1 I have illustrated my assembled 75 combination which comprises the frame structure consisting of the two side jamb members 10 and 12, and sill 14, and the head piece 16. Along the inner side of each of the jamb members 10 and 12 there is secured a pair of flexible metal guide strips one of each pair, 18 and 20, being illustrated in Fig. 1. 80

Each of the sash members consists of outer frame members 22, each of which is identical in structure and may be rolled from a sheet 85 of metal into the shape illustrated. These outer frame members 22 are joined at their corners by welding or soldering as desired. The inner frame members 24 are also all of identical structure and may be likewise rolled from a strip of metal into the illustrated desired shape. These frame members are secured as illustrated to the outer frame members in any desired manner, as by welding or soldering. A locking mechanism 26 is secured to the upper frame of the lower sash and cooperates with the vertical frame 24 of the upper sash to lock the sashes in any desired 90 relative position. The particular formation of the frame members 24 and the manner in 95 100

which they cooperate with the locking mechanism 26, as well as the glass panes, constitutes an important part of my invention but will be made the subject matter of a separate application and described in detail therein.

The formation of each pair of flexible metal guide strips 18 and 20 is clearly illustrated in Fig. 5 of the drawings. Each of them consists of a substantially V-shaped strip, the 10 arms of which are indicated by the numerals 28 and 30. While I do not intend to specify any particular metal which must be used in this structure, I have found that bronze constitutes a very suitable material because of 15 the high degree of flexibility and springiness which is inherent in that metal, particularly when formed into a strip of relatively small thickness.

The arm 28 of each strip is secured to the 20 jamb 10 at spaced apart intervals along the length thereof by nailing, or any other means which may be found desirable. While I have not illustrated such structure, I contemplate securing a metal lining longitudinally along 25 the length of each of the jambs and spot welding the arm 28 of each guide strip thereto at spaced apart points.

As is apparent from Fig. 5, two of these 30 guide strips are secured along the length of each of the window jambs 10 and 12 in parallel relation and the arm 30 of each is bent outwardly toward the sash frame member 22 and rolled at its outer extremity into a lip formation 32 which fits snugly into the groove 34 of rolled metal frame member 22. It will 35 be noted that aside from the bend 36, whereby the bronze sheet is formed into a substantially V-shaped member, there is a second bend 38 intermediate the length of the arm 40 30 which is produced by a light scoring of the metal. Each pair of guide strips secured along the jamb on each side are spaced apart a distance which will permit the lip portion 32 to fall into the groove portions 34 of the 45 upper and lower sash frames respectively.

While I have illustrated one form of securing the resilient guide strips along the inner face of the window jambs 10 and 12, I contemplate constructing the two bronze guide 50 strips of each pair in a single piece and providing a flange which may be inserted into a saw-back groove provided along the inner face of the jambs. It is obvious that such a construction would facilitate the assembly of 55 the structure and at the same time cut down the expense of manufacture on volume production. Such structure also would provide a more complete weather stripping.

It is therefore apparent that the upper and 60 lower sash members are adapted to slide along these guide strips, the said guide strips functioning not only as a guide, but exerting inwardly toward the center of the sashes a yielding pressure to retain each of them in 65 any position to which it may be raised or

lowered. Should any weakening of the pressure exerted by guide strips develop it may be remedied in any one of three ways, each of which is extremely simple and requires but little time. A wedge shaped tool may be 70 run along the bottom of the V to spread the V somewhat, a similar tool may be hastily run along within the lip 32 to spread the lip so that it will bear more forcefully against the side walls of the groove 34, or a scoring 75 tool may be run along the score 38 which will tend to spring the lip member further out toward the center of the sash.

I contemplate providing a strip of weather stripping material 39, such as felt, along the 80 inner face of at least one of the guide strips in order to provide a more complete weather stripping. Such a strip may be secured along the inner face of the arm 30 of the inner strip by gluing or other suitable means 85 prior to the assembling of the window structure.

While I have not, as already stated, described my frame members 22 or 24, with any amount of detail, it is obvious that they are so rolled as to provide the necessary grooves 34 along their outer edges and the tapered channel wall portions 40, which are adapted to cooperate with the glass pane 41 and putty 43 to form a more lasting, flexible joint than usual.

Secured along the underside of the head in any desired manner is a flange member 42 which constitutes a stop for the upper sash upon closing the same. This flange member has a depending portion 44 which drops from the head 16 and is provided with a rolled in portion 45 adapted to catch in the grooves 46 of the upper sash frame member 22. This will assist in retaining the upper sash in its closed position in the event that other means should fail and also provide an effective weather strip. Another weather strip piece 48 is secured by nailing, or any other suitable means, to the sill 14 and is turned into a U-shaped projection 50 as indicated in Fig. 3 which is adapted to seat within the groove 34 of the lower frame member 22 of the lower sash. As in the case of the flange 42 this lower piece 48 constitutes an effective stop 110 and weather stripping unit for the lower sash.

As is apparent, I have designed a window structure wherein sashes of inexpensive type may be utilized without the assistance of 120 sash weights to retain each of them in its adjusted position, the metal guide strips 18 and 20 on each side exerting a pressure inwardly upon each of the sashes to hold them in position. Furthermore, the pressure exerted upon the sashes to retain them in any desired position may be readily adjusted in any one of the several ways heretofore described without necessitating skilled labor of any sort.

My entire assembly is made up of units which are easy to manufacture and assemble, thus reducing the cost of the completed article as well as providing an efficient window structure.

5 While I have illustrated a preferred embodiment of my assembly, it is to be understood that I intend to limit myself only within the scope of the appended claims.

10 What I claim:

1. In combination with a window sash having a groove extending along the side thereof, a frame, and a substantially V-shaped spring metal guide strip secured along the 15 frame and adapted to seat within said groove.

2. In combination with an upper and lower window sash a pair of V-shaped flexible metal guide strips having one of their sides arranged in overlapping relation and in substantially the same plane, the other sides bearing 20 yieldingly against the sides of the upper and lower sash members respectively.

3. A window structure including, in combination, a sash having its outer frame members rolled to form a groove extending along the outer edge thereof, and an inwardly extending channel having tapered walls, the inner one of which is bent inwardly to form a seat for a glass pane.

30 4. In combination with window structure having a frame and an upper and lower sash, a weather strip secured along the head of the frame, said strip being rolled along its length to bear yieldingly against the upper frame of said upper sash to assist in holding the same in closed position.

5. In combination with a window structure having a frame and an upper and lower sash, resilient guide strips secured along each 40 vertical inner face of the frame and adapted to cooperate with the sashes to retain them in position, said guide strips including a pliant weather stripping material secured thereto.

45 6. In combination with a window sash, an outer frame member rolled from sheet metal to form a guide groove along its outer edge, and a bead of less than 90 degrees adapted to seat a glass pane.

50 7. Window structure comprising, in combination, a plurality of channel shaped cross frame members forming an upper and lower sash, side walls of each of said channel shaped frames being tapered to form with a flat portion of the frame a bead of less than 90° adapted to receive a glass pane.

55 8. A window sash comprising a plurality of rolled sheet metal frame members forming a rectangular frame, each member including a groove along its outer edge face adapted to receive a flexible guide strip, and a plurality of pane supporting channel shaped inner frame units within the outer frame member and secured thereto.

65 9. In combination with a window sash hav-

ing a guide groove extending along the vertical edges thereof, a guide strip of resilient metal formed into a pair of V-shaped portions extending at right angles to one another, one of said portions being adapted to slidably engage the groove in said sash.

10. A window sash guide strip comprising a resilient metal strip including a pair of V-shaped portions, said portions having one leg in common.

75 11. A window sash guide strip comprising a strip of resilient material bent transversely to form a pair of V-shaped portions, said portions being positioned perpendicularly with respect to one another.

80 12. A window sash guide strip comprising a strip of flexible material bent to form in cross section a pair of V-shaped portions having a common leg between them, the two other legs being of unequal length.

85 13. In combination with a window structure having a frame and an upper and lower grooved sash, resilient guide strips secured along each vertical inner face of the frame, said strips including a return bend portion, the outside of each of said portions being secured to the vertical face of the frame and in partially superposed relation, the extremities of the inner portion of each return bend being bent over to slidably engage the grooves in the sash members respectively.

90 In testimony whereof, I, ARTHUR T. BRENNAN, sign this specification.

ARTHUR T. BRENNAN.
